UNITED STATES PATENT OFFICE.

OTTO LAUBER, OF ESSEN-ALTENDORF, GERMANY, ASSIGNOR TO FRIED.
KRUPP, OF ESSEN, GERMANY.

GUN-CARRIAGE.

SPECIFICATION forming part of Letters Patent No. 708,235, dated September 2, 1902.

Application filed September 21, 1901. Serial No. 76,013. (No model.)

To all whom it may concern:

Be it known that I, OTTO LAUBER, engineer, a citizen of the German Empire, residing at 36 Grünstrasse, Essen-Altendorf, Germany, have invented certain new and useful Improvements in Gun-Carriages, of which the following is a specification.

The present invention has reference to improvements in gun-carriages, and particularly to apparatus for regulating the amount of recoil and the running-out movement, as described in Resow's United States Patent No. 620,360, dated February 28, 1899.

The object of this present invention is to simplify the construction of the apparatus described in said patent without essentially reducing its efficiency.

To this end my invention consists, essentially, in a recoil apparatus for field-gun carriages comprising a brake-spur, a thrust-bolt having a head engaging the spur, and a shank of wedge-shaped cross-section journaled at its forward end in a box affixed to the carriage, an adjustable friction-bearing 25 for the shank arranged in said box, and means for exerting an adjustable yielding pressure on the thrust-bolt through the bearing, whereby more or less friction is created between the surfaces of the shank of the bolt 30 and those of the bearings.

The nature of my invention will best be understood when described in connection with the accompanying drawings, in which—

Figure 1 represents a longitudinal vertical 35 section of part of a gun-carriage embodying my invention. Fig. 2 is a vertical section on the line 2 2, Fig. 1. Fig. 3 is a vertical section on the line 3 3, Fig. 1.

Similar letters of reference designate corresponding parts throughout the several views of the drawings.

In order that this invention may be more fully understood, I will proceed first to describe the general construction of the parts—40 for instance, as shown in Resow's United States Patent No. 620,360—and then describe the present improvement.

A designates the friction thrust-bolt, which during the recoil moves within a box D against 45 the frictional resistance caused by the pressure of screws f upon the springs g. This

bolt is slotted and circular in cross-section. According to my present invention the slot is dispensed with and the friction thrust-bolt is provided with plain wedge-shaped surfaces 55 and slides in correspondingly-formed ways of the compressible bearings or brasses in the box.

Referring now to the drawings, the letter A designates the thrust-bar, which is pushed 60 forward by the spur S during the recoil and compresses the spring-column B, which is supported thereon, as before, and abuts against and is guided within the bearing D. This thrust-bar A has its shank made substantially 65 square in cross-section, forming two wedge-shaped surfaces, and is supported in two bearings or brasses E, having wedge-shaped cavities therein and placed within the journaled box D, which is provided with means f and g 70 for its adjustment or compression.

In view of the arrangement described a higher frictional resistance is caused by the co-operation of the thrust-rod and the wedge-shaped surfaces on the pressure-bearings 75 than in the case of a circular cross-section for these parts, the frictional resistance increasing as the angle of the wedge-shaped surfaces is made more acute. By thus increasing the frictional resistance the notch in 80 the thrust-bar and the thrust-plate of the pressure-bearings may be omitted, and consequently the construction of the bar and that of the whole regulating devices are simplified. Of course the quadratic section of the thrust-bar, as shown, is not absolutely necessary, as the cross-section may be rhomboidal or triangular. Likewise the cross-section need not be the same for its whole length, but may increase from the front to the rear end—that 90 is, to correspond to the form of the rod in Patent No. 620,360—so as to obtain a constantly-increasing frictional resistance, since during the recoil the rod is pushed through the bearings.

What I claim as new is—

In a recoil apparatus for field-gun carriages, the combination with a brake-spur, a thrust-bolt engaging at one end with said spur, and having a solid angular shank and a 100 compression-box comprising two bearings or brasses provided with angular grooves, one

of said brasses being movable, said grooves embracing the angular faces of the thrust-bolt, whereby, without intervention of other mediums, pressure on one of said brasses produces friction between said grooves and the angular faces of said shank.

In testimony whereof I have hereunto set

my hand in the presence of two subscribing witnesses.

OTTO LAUBER.
